US00D996826S

(12) **United States Design Patent** (10) Patent No.: **US D996,826 S**
(45) Date of Patent: **** Aug. 29, 2023**

(54) **LUGGAGE**

(71) Applicant: **Jeffery Baron Lesperance**, Howell, MI (US)

(72) Inventor: **Jeffery Baron Lesperance**, Howell, MI (US)

(**) Term: **15 Years**

(21) Appl. No.: **29/788,779**

(22) Filed: **Jul. 27, 2021**

(51) LOC (14) Cl. **03-01**

(52) U.S. Cl.

USPC **D3/318**

(58) **Field of Classification Search**

USPC ..... D3/231-233, 243-246, 249-253, 263, D3/268-267, 294, 318, 905, 217, 289, D3/279, 232, 276, 273, 218, 282, 247, D3/301, 201, 283, 303, 216, 255, 295, D3/274, 265, 900, 302, 304, 287, 284, D3/299, 254, 290, 226, 321, 903, 203.1, D3/245, 205, 281, 269, 320, 262, 901, D3/260, 319, 206, 272, 315, 285, 291, D3/215, 204, 238, 244, 292, 327, 270, D3/264, 278, 203.3, 313, 212, 902, 234, D3/307, 271.1, 297, 323, 202, 203.2, 314, D3/219, 221, 298, 261, 328, 904, 288, D3/312, 230, 300, 250, 271.2, 228, 286, D3/208, 266, 229, 256, 296, 293, 275, D3/305, 306, 20, 271.4, 248, 257, 310, D3/252, 203.5, 235, 258, 271.12, 308, D3/251, 11, 271.5, 309, 311, 317, 324, D3/271.3, 322, 203.6, 224; 190/18 A, 190/115, 109, 110, 127, 111, 107, 102, 190/108, 103, 119, 903, 18 R, 124, 1, 190/125, 11, 122, 902, 39, 113, 100, 112, 190/126, 8, 2, 16, 901, 28, 121, 101, 106, 190/114, 120, 900, 12 R, 37, 117, 26, 190/105, 13 R, 24, 116, 15.1, 36, 123,

(57) **CLAIM**

The ornamental design for a luggage, as shown and described.

DESCRIPTION

FIG. 1 is a back perspective of a first embodiment of a luggage showing my new design;

FIG. 2 is a top view thereof;

FIG. 3 is a front perspective of a second embodiment of the luggage;

FIG. 4 is a top view thereof;

FIG. 5 is a front perspective of a third embodiment of the luggage; and,

FIG. 6 is a top view thereof.

The dashed broken lines depict portions of the luggage that form no part of the claim.

1 Claim, 3 Drawing Sheets
